TEXTILE YARN MANDREL

Eugene Sinnett, Vienna, W. Va., assignor, by mesne assignments, to L-O-F Glass Fibers Company, Toledo, Ohio, a corporation of Ohio

Application March 27, 1953, Serial No. 344,964

4 Claims. (Cl. 242—68)

The present invention relates broadly to the art of winding, and more particularly, is concerned with a new and improved mandrel for supporting packages of filamentary materials during the winding and other allied processing operations.

During the production of the textile fibers, such as for example glass fiber strands and yarns, it is frequently necessary that the fibers be rewound onto various types of spools or bobbins in order that operations such as twisting or plying may be readily accomplished, and that the fibers be on that type of spool which is most suitable for use with the customer's fiber processing equipment. Thus, by way of illustration, it has been the practice in the fiber glass art to remove the newly formed strands from supports onto which they are received during the forming operation, and, after twisting or plying the strands, to wind the yarns formed of said strands onto cones or spools which are designed especially for the twisting or plying equipment. Thereafter, if the needs of the customer require the yarns to be on a particular type of spool and/or to be coated with a surface treating substance, said yarns are wound onto a package particularly adapted to the customer's manufacturing equipment.

By way of further illustration, many electrical equipment manufacturers are utilizing glass fiber yarns for a wide variety of purposes because of their high heat resistance, high dielectric strength and low space factor. And because of the structural characteristics of the equipment of said manufacturers, they demand that the fibrous yarns be furnished on what are known as "split-tube serving packages" because of the ease with which said tubes, when exhausted, may be removed from their equipment.

Prior to the present invention, however, there has been a reluctance on the part of the glass fiber producers to furnish, and a hesitancy on the part of the electrical equipment manufacturers to accept, fibrous glass yarns on split tubes. The principal reason for this has been the looseness of the yarns on said tubes, and this has been due to a great degree to the particular construction of the mandrel upon which split tubes have been carried.

Generally speaking, the mandrel heretofore employed has operated on an expansion principle to maintain the split tube in rigid and tight relation. A typical construction has comprised a hollow metallic shaft having diametrically opposed slots extending along a portion of its length, and a tapered member which is inserted into the shaft bore to cause expansion of the split segments of the shaft. In utilizing a mandrel of this type, the tapered member quite frequently requires a tool to effect its removal from the shaft, and after said removal, the split tube is passed onto said shaft. Thereafter, the tapered member is inserted into the shaft bore a sufficient distance to expand the shaft segments into firm contact with the inner walls of the tube to thereby main-

2

tain it in rigid relation with said walls during the yarn winding operation.

However, experience has indicated that even though the split tube upon location on the mandrel was not expanded to a degree sufficient to cause separation between its ends, when the winding operation was completed and the loaded tube removed from the mandrel, the yarns carried on said tube were only loosely wrapped thereon. This disadvantageous situation is apparently the result of contraction of the yarn, which in turn is caused by the weight of the yarns themselves and the tight condition in which they are wound. In addition, it would appear that the tube is expanded during the winding of yarns thereon due also to the high speed at which the mandrel rotates.

Packages carrying loosely wound yarns are of course generally commercially undesirable due to the difficulty encountered in their ready removal, and one manner of avoiding the difficulty has been to employ solid rather than split tubes in the fiber manufacturing operation. However, since solid tubes are inconvenient to use on the customer's fabricating equipment, they constitute a generally unsatisfactory commercial substitute.

It is therefore an important aim of the present invention to provide a new and improved mandrel for use in the winding of filamentary materials, which mandrel maintains the filament receiving tube or package in secure relation thereon and permits the packaging of tightly wound filaments on said tube.

Another object of the invention is to provide a mandrel for supporting tubes during the winding of filamentary materials thereon, characterized by the exertion of little, if any, expansive force on the inner diameter of the tube or package, and further characterized by the use of compressive force on opposite ends of the tube.

Another object of the invention lies in the provision of a mandrel which is readily removable from its supporting and driving shaft, and which comprises a substantially cylindrical tube supporting member and a readily removable cap member which is carried by said shaft and which is mounted on said supporting member in overlapping relation therewith.

Other objects and advantages of the invention will become more apparent during the course of the following description when taken in connection with the accompanying drawing.

In the drawing wherein like numerals are employed to designate like parts throughout the same:

Figure 1 is a perspective view of winding apparatus embodying a mandrel of the present invention;

Figure 2 is a perspective view of a split winding tube with which the present mandrel is particularly adapted;

Figure 3 is a detail sectional view of the mandrel carried upon a suitable driving shaft and shown supporting a winding tube of the character illustrated in Figure 2;

Figure 4 is an exploded perspective view of the mandrel of Figure 3; and

Figure 5 is a detail sectional view of a modified form of mandrel.

Although the mandrel disclosed in the foregoing views of the drawing and hereinafter described is particularly adapted to the winding of glass fiber strands and yarns, it will be appreciated that it is also well suited as a support for the various textile and resinous fibers, and for such other uses as the winding of fine diameter wire.

As has been noted, it is frequently necessary to rewind glass fiber yarns from the tubes or bobbins utilized during the twisting or plying operation onto a tube of a particular shape and design which is more readily handled upon the customer's manufacturing equipment.

As was also noted, during such a rewinding operation

various treatments may be applied to the glass fibers to modify the surface characteristics thereof for particular end uses.

Apparatus well suited to accomplish these purposes is illustrated in the drawing and reference is now made particularly to Fig. 1, thereof. As shown, a plurality of twisted yarns 10, which may or may not be also plied, are drawn from the desired number of glass fiber cones or tubes 11 through closed guide eyes 12 between hook guide eye 13 and over a surface treatment roller 14 partially immersed in a tank 15 of the chosen coating material. After passage over the roller 14 the coated yarns are fed between additional hook guide eyes 16 through a tensioning device 17 and are joined in parallel relation by a traversing guide 18 prior to being fed onto a tube or package sleeve 19 carried by the mandrel 20 of the present invention. The mandrel is supported upon a shaft 21 driven by a belt and pulley arrangement 22 connected to a source of power (not shown). Drive means 23 may be provided for the surface treatment roller 14 and this may also operate from the same source of power.

The foregoing process is known in the art as the "multiple end winding operation" and is presently most frequently used in the production of multiple end yarns from single end yarns for use in the reinforcement and insulation of electrical wire and cable. For this purpose two or more single end yarns may be combined, depending upon the degree of improvement in insulative and reinforcing properties desired, and the particular surface treatment may likewise be varied. Mineral oil, tricresyl phosphate, silicones, and other suitable substances may be employed to modify the surface characteristics of the glass fibers.

It has been found desirable that the glass fiber yarns as thus treated and wound be on a particular tube in order to be readily manipulated on the braiding equipment of the electrical manufacturer. One such tube which has been utilized with much success is shown in Figure 2 and this is termed a "serving package." This package, designated generally by the numeral 24, comprises the tube or package sleeve 19, previously referred to, provided with a split or cut 25 longitudinally thereof and a pair of tube flanges 26 carried upon the circumference of the sleeve at the opposite ends thereof. The sleeve 19 and tube flanges 26 are preferably formed of a relatively heavy composition pressed fiberboard and the outer circumference of the sleeve is provided with a relatively rough surface to maintain the glass yarns in place thereon. As is shown, the tube flanges 26 are not carried by the sleeve 19 during the end winding operation, but are located on the sleeve after the yarns have been wound thereon and the sleeve removed from the mandrel 20.

Looseness of the yarns after completion of the winding operation, apparently caused primarily by the use in the prior art of an expansive force on the inner walls of the package sleeve to maintain said sleeve on a mandrel, is herein substantially avoided by the provision of a mandrel 20 having the structural features shown in Figures 3 and 4 of the drawing. It will be seen that the mandrel is carried upon the supporting and driving shaft 21 which is formed to provide at one end an exposed reduced portion 27 connected to the belt and pulley arrangement 22, and a raised relatively thicker portion 28 having a keyway 29 extending longitudinally thereof. Also comprising a part of the shaft 21 and arranged adjacent the raised portion 28 at its opposite end is a set of external screw threads 30 provided on the normal diameter of the shaft 21. Spaced from said set of threads 30 and turned onto a reduced section of the same shaft 21 is another set of external threads 31 arranged on the outermost part of said shaft 21.

The mandrel 20 itself comprises a substantially cylindrical tube or body member 32 provided at one end with an integral flange 33 and at the opposite end with a

removable cap member 34, encircling or overlapping the body member 32. Said member 32 is carried by the raised relatively thicker portion 28 of the shaft and is secured thereon by a key 35 slidable in the keyway 29. In addition, the body member 32 is locked to the shaft 21 by a collar 36 having internal screw threads 37 which turn upon the threads 30 of the shaft 21 to thereby force the leading surface 38 of the collar 36 against the formed vertical wall 39 of the body member 32. The collar is further provided with a plurality of spaced holes 40 for the reception of the pins of a suitable wrench.

The removable cap member 34 has an inner wall diameter only slightly in excess of the outer diameter of the body member 32 and is provided with a set of internal threads 41 engageable with the threads 31 on the end portion of the shaft 21. Preferably the number of threads is not more than four in order that the cap member may be rapidly turned by hand onto the shaft 21 and the tube sleeve held firmly against the flange 33 with a minimum number of turns of the cap member 34. As shown, the shape of said member corresponds generally to a cylinder closed at one end, and at said end centrally thereof is located the set of internal threads 41. On the outer surface of the closed end and integral therewith there is provided a cap locking nut 42 which may be used to accommodate a suitable wrench when it is desired to tighten the member 34 on the shaft 21 with a greater force than that normally provided by hand action.

Assembly of the present mandrel 20 is accomplished by sliding the cylindrical body member 32 onto the shaft 21, and particularly, onto the raised relatively thicker portion 28 thereof. The key 35 is then inserted into the keyway 29 a distance sufficient to make a firm contact with the adjacent wall of the body member 32 and base of the keyway. The collar 36 is then turned tightly onto the innermost threaded portion or screw threads 30 of the shaft 21 and made secure thereon by a pin wrench or similar means. The tube sleeve 19 is thereafter passed onto the body member 32 and against the integral flange 33, whereupon, the cap member 34 is passed over the body member and tightened by engagement of the outermost threads 31 of the shaft 21 with the threads 41 of said cap member. The tightening action is continued until the open-ended outer wall of the cap member bears firmly against the end wall 43 of the tube sleeve 19 with sufficient compressive force to prevent slippage of said sleeve on the mandrel during high speed rotation thereof. By virtue of the compressive action accomplished, which holds the sleeve tightly between the flange 33 and cap member 34, there is no tendency for the sleeve to open up along its split or cut 25 either when being tightened upon the mandrel, during rotation of the mandrel, or upon removal therefrom after completion of the winding of the yarns upon said sleeve. In this manner, the possibility of the yarns being or becoming loose upon the sleeve is substantially remote.

Upon completion of the winding operation the sleeve 19 with the desired length and weight of glass fiber yarns 60 44 thereon is removed by first hand loosening the cap member 34 and sliding the sleeve rearwardly off the body member. Tube flanges 26 are thereupon located upon the ends of the sleeve and the serving package is completed and in the form shown in Figure 2.

Another advantage resulting from the structure herein disclosed is that mandrels of varying outer diameters may be utilized without the necessity of replacing the supporting and driving shaft. Inasmuch as tube sleeves 70 are available in such diameters as 1 1/4, 1 1/8, 1 1/4 and 2 1/4 inches, mandrels provided with body members of substantially the same outer diameters can be readily used on the same driving shaft by having a uniform inner diameter on said members and by merely locating said members and their companion parts in the manner above

described with reference to the assembly of the mandrel 20. Heretofore when it was desired to change mandrels it was necessary to also replace the shaft since they were integral parts.

The foregoing noted objective of avoiding looseness of the yarns may also be accomplished by the provision of a mandrel of the character shown in Figure 5. As illustrated, the mandrel 45 comprises a removable cap member 46 having a threaded portion 47 protruding outwardly of the center which is receivable within a threaded recess 48 arranged centrally of one end of the mandrel. The body member or tube 49 may be provided at its opposite end with an integral flange 50 as herein described and the threaded portion 47 of the cap member 46 may be turned into the recess 48 of the body member 49 so that compression is placed on the opposite ends of the tube sleeve 51 by the flange 50 and vertical wall 52 of the cap member 46. By this arrangement, opening of the longitudinal split in the package sleeve 51 is avoided and the sleeve securely maintained on the tube 49 during rotation thereof.

It is to be understood that the form of the invention herewith shown and described is to be taken as a preferred embodiment of the same, but that various changes in the shape, size and arrangement of parts may be resorted to without departing from the spirit of the invention or the scope of the subjoined claims.

I claim:

1. A rotatable mandrel for winding fibrous materials, comprising a supporting shaft provided at one end with a pair of spaced sets of screw threads, an open-ended cylindrical tube carried upon said shaft, means on said shaft securing said tube thereon for rotation therewith, a package sleeve having a split longitudinally thereof mounted upon said tube and rotatable therewith, means on said tube engaging one end of the sleeve, and means carried by the tube engaging the opposite end of the sleeve and urging said sleeve against said second-named means to compress the same endwise and to prevent opening of the split in the sleeve during rotation thereof.

2. A rotatable mandrel for winding fibrous materials, comprising a supporting shaft provided at one end with a pair of spaced sets of screw threads, an open-ended cylindrical tube carried upon said shaft and provided at one end with an integral flange member, a collar adapted for threaded engagement with one of said sets of screw threads and adapted to secure said tube upon said shaft, a package sleeve mounted upon said tube with one end

in abutting relation with the flange member, and means carried by the other of said sets of screw threads for compressing said sleeve endwise against said flange member.

3. A rotatable mandrel for winding fibrous materials, comprising a supporting shaft provided at one end with a pair of spaced sets of screw threads, an open-ended cylindrical tube carried upon said shaft and provided at the end located most distant from said sets of screw threads with an integral flange, means adapted for threaded engagement with one of said sets of screw threads for securing said cylindrical tube upon said shaft, a package sleeve mounted upon said tube with one end in abutting relation with the flange and rotatable with said tube, and means having a threaded bore engageable with the other set of threads to compress the package sleeve endwise against the flange.

4. A rotatable mandrel for winding fibrous materials, comprising a supporting shaft provided at one end with a pair of spaced sets of screw threads, an open-ended cylindrical tube carried upon said shaft and provided at its end positioned most distant from said screw threads with an integral flange member, means on said shaft for locking said tube thereto in non-rotatable relationship, means adapted to engage one of said sets of screw threads for securing said cylindrical tube upon said shaft in a fixed axial position in cooperation with said locking means, a package sleeve provided with a longitudinally extending seam mounted upon said tube in abutting end relationship with said flange and rotatable with said tube, and a cylindrical cap member having a threaded bore engageable with said other set of screw threads on said shaft and engaging the other end of the package sleeve to press the sleeve endwise against said flange member and thereby prevent opening of the seam of the sleeve during rotation thereof.
